(57) **CLAIM**

The ornamental design for a photovoltaic power optimizer, as shown and described.

DESCRIPTION

1. Photovoltaic power optimizer

1.1 : Perspective

1.2 : Perspective

1.3 : Front

1.4 : Back

1.5 : Left

1.6 : Right

1.7 : Top

1.8 : Bottom

(Continued)

FIG. 1.1 to FIG. 1.8 show a photovoltaic power optimizer to embodiments of the present design, respectively.
